NEUTRALIZED RADIO-FREQUENCY
AMPLIFIERWillis E. Phillips, Deerfield, Ill., assignor to
Zenith Radio Corporation, Chicago, Ill., a cor-
poration of Illinois

Application January 11, 1943, Serial No. 471,960

13 Claims. (Cl. 179—171)

1

This invention relates to neutralized radio frequency amplifiers and particularly to such amplifiers which are employed at ultra-high frequencies, of the order of above thirty megacycles.

It is well known that the electrodes of a thermionic tube, and particularly the plate and control grid, have a definite capacity through which the output and input circuits are coupled together. To prevent excessive feed-back and regeneration, a neutralizing condenser having approximately the same capacity as that existing between the grid and plate is arranged to supply an equal amount of energy of opposite phase from the plate to the control grid. In the case of push-pull amplifiers, the plate of each tube is usually connected through a neutralizing condenser to the control grid of the other tube.

When such conventional circuits are embodied in ultra-high frequency amplifiers, considerable difficulties are experienced. This is particularly true where large tubes are employed because the neutralizing leads or conductors have, in that case, and particularly in the case of push-pull amplifiers, to be of a length which is a substantial fraction of the wave length. At ultra-high frequencies the neutralizing conductor has a very substantial reactance and the neutralizing condenser and the neutralizing conductor have a very large distributive capacity to ground, a capacity which may approach that of the neutralizing condenser itself.

I find that in some cases the neutralizing conductor and the plate of the neutralizing condenser to which it is attached acquire very high voltages. In some cases, the condenser arcs over, and arcs extend out of the conductor and into the air. This high voltage may become so large in high-power ultra-high frequency amplifiers as to be the limiting factor in determining the maximum power that may be produced by such an amplifier. Furthermore, the input tuned circuit is effectively shunted by the inductance of the neutralizing conductor and the distributive capacity of the conductor and the neutralizing condenser so that the inductance of the input circuit must be seriously limited. In many cases, it is found that even though the capacity of the input circuit be eliminated, it is not possible to tune the input circuit to the ultra-high frequency to which it is desired to operate the amplifier.

The principal object of the invention is to provide a neutralized ultra-high frequency amplifier in which these disadvantages are obviated.

A further object of the invention is to provide a neutralized ultra-high frequency amplifier in

2

which the neutralizing conductor and the neutralizing condenser have no excessive voltage.

Other objects, advantages and capabilities of the invention will appear from the following description of preferred embodiments thereof taken in conjunction with the accompanying drawing, in which:

Fig. 1 is a wiring diagram of a single tube ultra-high frequency amplifier provided with a neutralizing circuit embodying my invention;

Fig. 2 is a similar diagram of a modified form of the invention;

Fig. 3 is a wiring diagram of an ultra-high frequency push-pull amplifier provided with neutralizing circuits embodying my invention;

Fig. 4 is a diagrammatical view of a physical embodiment of a high-power, ultra-high frequency amplifier constructed in accordance with the wiring diagram of Fig. 3, and

Fig. 5 shows an alternative specific connection in the arrangement shown in Figure 3.

Referring to the drawing and particularly to Fig. 1 thereof, the reference numerals 10 and 11 designate the inductance and tuning condenser 15 of the input circuit which is connected to the control grid 12 of the thermionic tube 13. The plate 14 of the tube 13 is connected to one terminal of the tuned circuit 15 which has its other terminal connected by a by-pass condenser 16 to the cathode 17. A source of high voltage 18 is connected to the junction point of circuit 15 and condenser 16. The plate 14 is connected through a neutralizing condenser 19 to a conductor 20 which is connected to the low side of the inductance 10. The conductor 20 has at ultra-high frequencies a relatively high reactance which is illustrated by the coil 21. The reactance may attain very high values and consequently it is shown as a full line coil 21 notwithstanding the fact that the conductor 20 is a solid piece of copper.

In Fig. 1 I illustrate as the capacity 22 the distributive capacity of the conductor 20 and the plate of the condenser 19 to which it is attached. This distributive capacity provides a low reactance path at ultra-high frequencies. The value of capacity 22 may approach the value of the neutralizing condenser 19 and consequently it is shown in full lines as a condenser.

In accordance with the present invention I connect an inductance 23 between the conductor 20 and the plate of the condenser 19 to which it is attached and ground. This inductance 23 may be of the order of a few microhenries.

I have found that the objectionable high volt-

age produced in the conductor 20 and in the plate of the condenser 19 to which it is attached results from the fact that the inductive reactance 21, together with the capacitive reactance 22, constitutes, at ultra-high frequencies, a series resonant circuit. My introduced inductance 23 destroys this series resonant circuit. Preferably it constitutes, with the distributive capacity 22, a parallel resonant circuit which has a high resistance to the ultra-high frequency current. That is, the inductance or inductor 23 is connected in parallel with the distributive capacity 22 of said conductor 20 and condenser 19 and one terminal of inductance 23 is connected adjacent the junction of conductor 20 and condenser 19. Before the introduction of my inductance 23, a large resonant current flowed from the conductor 20 to ground, through the easy path provided by the distributive capacity 22, and this high current resulted in the excessively high voltage of the conductor 20 and of the plate of the condenser 19 to which the conductor 20 is connected. The parallel resonant circuit 22, 23 cuts down this ultra-high frequency current to a minimum, and thus the objectionable high voltage is destroyed.

The inductance value of the inductor 23 is best determined practically. Thus I introduce an inductor 23 which is obviously too large and I adjust the condenser 19 for optimum neutralization. I determine the voltage of the conductor 20 and the plate of the condenser 19 to which it is attached. In high-power installations I may contact the plate of the condenser 19 with a metal rod held on an insulating handle. On withdrawing the rod, an arc will extend between the condenser 19 and the end of the rod, owing to the objectionable high voltage. By progressively decreasing the inductance value of the inductor 23 I find that the arc which can thus be drawn becomes less and less, and the final steps of adjustment may be performed with the aid of a glow lamp until, when I have an inductor 23 of the correct inductance value, no excessive voltage can be discovered on the plate of the condenser 19 to which the conductor 20 is attached. When that end is attained, the distributive capacity 22 and the inductor 23 are believed to constitute a parallel resonant circuit at the ultra-high frequency. As the value of inductance 23 is progressively decreased, the capacity of the condenser 19 has to be progressively increased to provide proper neutralization. When set correctly, the condenser 19 has a capacity approximately equal to that existing between the grid 12 and the plate 14.

In Fig. 2 I have shown the wiring diagram embodying my invention in another conventional neutralizing circuit. In this circuit the neutralizing condenser 19 has one of its terminals connected to the low end of the output tuned circuit 15 and its other terminal connected by means of a conductor 20 to the control grid 12 through the unnumbered condenser. In this case the inductive reactance of the conductor 20 is illustrated as the coil 21 and the distributive capacity of the conductor 20 and the plate of the condenser 19 to which it is attached is also illustrated as the capacity 22.

My introduced inductor 23 has one of its terminals connected to the plate of the condenser 19 to which the conductor 20 is connected and its other terminal connected to ground. At the final adjustment the inductor 23 constitutes with the capacity 22 a parallel circuit resonant at the ultra-high frequency and the capacity of the con-

denser 19 closely approximates the capacity between the plate 14 and the control grid 12.

In Fig. 3 I have shown a preferred manner in which my invention is embodied in a push-pull amplifier provided with neutralizing circuits extending from the plate of one tube 14 to the control grid of the other tube 12. Each neutralizing circuit comprises a neutralizing condenser 19 connected to the plate of one tube, which neutralizing condenser is connected by a conductor 20 to the grid of the other tube. Here again the inductive reactance of the conductor 20 is illustrated as a coil 21 and the distributive capacity of each conductor 20 and the plate of the condenser 19 to which it is attached is illustrated as a capacity 22.

This circuit is preferred for high-power, ultra-high-frequency amplifiers since the neutralizing circuits can be kept relatively short. Nevertheless, since the tubes used must be physically large for high-power amplifiers, the conductors 20 have substantial length and objectionable high voltages are found on these conductors and on the plates of the condensers to which they are connected. It will be understood that the objectionable high voltage increases with increase of frequency.

In this case, in Fig. 3 also, I may correct the circuit by connecting a coil 23 between each condenser 19 and ground in the manner described above in relation to Figs. 1 and 2. In practice, however, I prefer to connect a single inductor 23 between the two condensers 19, in the manner shown in Fig. 3. The center of the inductor 23 is a neutral or zero point and it may be grounded if desired as shown in Figure 5. It is thus seen from Figures 3 and 5 that the inductor 23 may constitute either a single inductor or in effect two inductors for achieving the purposes of the present invention. The steps of determining the proper inductance value of the inductor 23 are the same as previously described. In the final condition of adjustment each condenser 19 is adjusted to correspond to the plate to grid capacity of the tubes and each half of the inductor 23 constitutes, with the adjacent capacity 22, a parallel resonant circuit at the ultra-high frequency.

In Fig. 4 I show diagrammatically a physical embodiment of a high-power, ultra-high frequency amplifier constructed in accordance with the wiring diagram of Fig. 3. This amplifier comprises two high-power, water-cooled triodes 13 which include two depending copper cylinders 24 which are bridged across by a metal bar 25 to which the high voltage source 18 is connected by means of a conductor 26, the cylinders 24 being connected to the plates of the tubes. The output tuned circuit 15 is constituted by adjustable condenser plates 27, a metal bar 28 slidably mounted on the cylinders 24 and a swingable loop or stirrup 29 connected to the output leads 30. The neutralizing condensers 19 are constituted by arcuate plates 31 which are adjustably mounted so that they can be brought into proper spaced relation with cylinders 24. The arcuate plates 31 are connected by the conductors 20 to grid terminals of the tubes 13, the conductors being arranged criss-cross fashion and in spaced relation. The inductor 19 is constituted by two metal bars 32, the ends of which are connected to the grid connectors of the tubes. The bars 32 are bridged, remote from these ends, by a metal block 33 arranged to establish desired inductance for the inductor 19. The capacitor 11 is constituted by

an adjustable grounded plate 34 arranged to move between the bars 32 to provide proper tuning capacity for the grid circuit. Grid energy is supplied to the inductor 10 by means of a loop 35 arranged immediately below the bars 32. Filament energy is provided by the coaxial lines 36, the interior conductor being connected to one filament terminal on the tube 13 and the outer conductor being connected to the other filament terminal of the tube 13.

The inductor 23' is connected between the two plates 31. This inductor may take the form of a stout copper wire formed with a few coil turns depending upon the necessities of the installation. In practical cases it may have an inductance of a few microhenries, which is sufficient at ultra-high frequencies to provide a high reactance. Thus, at 50 megacycles one millihenry has a reactance of more than three hundred thousand ohms, and ordinarily a mere fraction of that inductance is sufficient to provide the desired effect.

It will be noted that in the single-tube amplifier shown in Figs. 1 and 2 the input tube circuit 10, 11 is shunted by the tuned circuit 21, 22 in the absence of the added inductor 23. In some cases, even with a very small inductance 10 and the omission of a physical condenser 11, it is impossible to get the frequency sufficiently high. The provision of the added inductor 23 or 23' as the case may be greatly reduces the shunt loading across the tuned circuit and permits a more favorable ratio of L to C and allows the amplifier to be operated at a higher frequency. Furthermore, the loading of the plate tuned circuit 15 by the shunting effect of capacities 19 and 22 is reduced by the provision of the inductor 23 permitting higher frequency operation and reducing losses in the tank circuit 15. The same effects are attained in the push-pull circuit shown in Fig. 3 and illustrated in Fig. 4.

Although the invention has been described in connection with details of specific embodiment thereof, it must be understood that such details are not intended to be limitative of the invention except insofar as set forth in the accompanying claims.

I claim:

1. In an ultra-high frequency power amplifier including a thermionic tube and a neutralizing condenser and a neutralizing conductor for supplying plate energy to a control grid, the combination with said neutralizing elements of an inductor of substantially no resistance arranged in parallel with the distributive capacity of said conductor and condenser and connected thereto adjacent their junction.

2. In a push-pull ultra-high frequency power amplifier including a pair of thermionic tubes, a pair of neutralizing condensers and neutralizing conductors connecting the plate of each tube to the control grid of the other tube, the combination with said neutralizing elements of an inductor arranged in parallel with the distributive capacity of each conductor and condenser and connected adjacent the junction of each conductor and its condenser.

3. In a push-pull ultra-high frequency power amplifier including a pair of thermionic tubes, a pair of neutralizing condensers and neutralizing conductors connecting the plate of each tube to the control grid of the other tube, the combination with said neutralizing elements of an inductor connecting a point adjacent the junction between one said condenser and its associated conductor to a point adjacent the junction be-

tween the other said condenser and its associated conductor.

5 4. In an ultra-high frequency power amplifier including a neutralizing condenser and a neutralizing conductor which develops excessively high voltages as a result of the reactance of said conductor at ultra-high frequencies, the combination of an inductor of substantially no resistance in parallel with said conductor and connected to 10 a point of excessive high voltage, said conductor having sufficient reactance to diminish substantially said excessively high voltage.

15 5. A neutralizing circuit including a neutralizing condenser and a neutralizing conductor, said condenser and conductor having a substantial distributive capacity and said conductor having sufficient length whereby at ultra-high frequencies said distributive capacity and the impedance of said conductor tend to constitute a resonant circuit with the production of excessively high voltages on said condenser and conductor, in combination with an inductor of sufficient reactance connected adjacent the junction between said condenser and conductor to provide with said distributive capacity a parallel resonant circuit at 20 said frequencies whereby the first said resonant circuit is effectively destroyed and the excessively high voltages resulting therefrom are prevented.

25 6. A neutralizing circuit including a neutralizing condenser and a neutralizing conductor having a substantial distributive capacity and said conductor having sufficient length whereby at ultra-high frequencies said circuit resonates, producing excessively high voltages therein, and a reactor of substantially no resistance connected to said circuit adjacent the junction between said condenser and conductor for effectively destroying the resonance thereof and effectively nullifying 30 said excessively high voltages.

35 7. In a push-pull, ultra-high frequency power amplifier including a pair of thermionic tubes, a pair of neutralizing condensers and neutralizing conductors connecting the plate of each tube to the control grid of the other tube, each condenser and conductor having a high distributive capacity 40 and each conductor having sufficient length whereby each conductor and its condenser tend to resonate at ultra-high frequencies, producing excessively high voltages therein, and a reactor of substantially no resistance connecting points 45 adjacent said condensers whereby the tendency to resonate and to produce ultra-high frequencies, 50 is effectively nullified.

55 8. In an ultra-high frequency power amplifier circuit, including at least one thermionic tube having plate and grid and a neutralizing condenser and a neutralizing conductor for supplying plate energy to said grid, the neutralizing condenser being adjacent a plate and the neutralizing conductor being relatively long, and an inductor of substantially no resistance in parallel 60 to said conductor connected adjacent the junction of said conductor and said condenser.

65 9. In a push-pull, ultra high frequency power amplifier, including a pair of thermionic tubes, a pair of neutralizing condensers adjacent the plates of said tubes and relatively long neutralizing conductors connecting the neutralizing condenser of one tube to the control grid of the other tube, and an inductor of substantially no resistance connecting said conductors adjacent their junction with their associated condensers.

70 10. In a push-pull ultra high frequency power amplifier including a pair of thermionic tubes, at least one neutralizing condenser and one neutralizing conductor connecting the plate of each tube 75

to the control grid of the other tube, the combination with said neutralizing elements of an inductor connected in parallel with the distributive capacity of said conductor and condenser and connected adjacent the junction of said conductor and said condenser.

11. In a push-pull ultra high frequency power amplifier including a pair of thermionic tubes, a pair of neutralizing condensers and neutralizing conductors connecting the plate of each tube to the control grid of the other tube, the combination with said neutralizing elements of one inductor arranged in parallel with the distributive capacity of one of said conductors and one of said condensers and connected adjacent the junction of said one conductor and said one condenser.

12. In an amplifier including a thermionic tube operable at a desired frequency and a neutralizing condenser and a neutralizing conductor for sup-

plying plate energy to a control grid, the combination with said neutralizing elements of an inductor arranged in parallel with the distributive capacity of said conductor and condenser, said inductor and distributive capacity comprising elements of a parallel tuned circuit tuned to said desired frequency.

13. In a push-pull amplifier including a pair of thermionic tubes operable at a desired frequency, at least one neutralizing condenser and one neutralizing conductor connecting the plate of each tube to the control grid of the other tube, the combination with said neutralizing elements of an inductor connected in parallel with the distributive capacity of said conductor and condenser, said inductor and distributive capacity comprising elements of a parallel tuned circuit tuned to said desired frequency.

WILLIS E. PHILLIPS.
